UNITED STATES PATENT OFFICE.

GEORGE F. BARBER, OF DE KALB, ILLINOIS.

NAIL-HOLDING ATTACHMENT FOR HAMMERS.

SPECIFICATION forming part of Letters Patent No. 299,717, dated June 3, 1884.

Application filed March 31, 1884. (No model.)

To all whom it may concern:

Be it known that I, GEORGE F. BARBER, of De Kalb, in the county of De Kalb and State of Illinois, have invented an Improved Nail-Holding Attachment for Hammers, of which the following is a full, clear, and exact description.

This invention has for its object the providing of a convenient appendage to hand-hammers for holding and starting nails when only one hand can be used or where the work is out of reach by the hand to hold the nail at starting; and the invention consists in a special construction and combinations of parts in a nail-holding hammer attachment, substantially as hereinafter described and claimed.

Reference is to be had to the accompanying drawings, forming a part of this specification, in which similar letters of reference indicate corresponding parts in all the figures.

Figure 1 represents a partly broken and sectional side view of a hammer-head with a portion of the hammer-handle having my nail-holding attachment applied and with a nail in position for being entered by the hammer through means of said attachment; and Fig. 2 is a transverse section on the line *xx* in Fig. 1.

A is the handle, and B the head, of the hammer.

C is a wedge driven into the outer end of the handle and protruding therefrom, so as to form a stop or back support for the head of the nail D to be entered in the work. This nail-head back stop or support is designed to remain permanently in the handle.

E is a stout spring-clamp, of broken circular form, adapted to closely hug the nose of the head of the hammer at a suitable distance back of its face *b* and to have a firm grip on the hammer-head. Firmly secured by rivets or otherwise to the top of this clamp is a shank or tongue, F, which may be made of spring-steel, and which, running backward, is bent at its rear end to enter the outer end of the handle, and serves not only as a guide or rest for the nail, but also as an anchor to hold the clamp E to its place, the clamp in turn also serving to firmly hold the tongue, so that it will not be jarred from its place in the hammer-handle.

Having thus fully described my invention, I claim as new and desire to secure by Letters Patent—

heaviest blows. The tongue F should be made sufficiently strong, so that it will not rise, when driving the nail, after it has been entered in the work.

G G are two spring-jaws, made much lighter and more pliable than the clamp E, to the outer sides of which they are attached. These jaws extend from beneath the clamp E to some little height above where their free ends or tips are curved or set back, to receive the shank of the nail D down between them. Said jaws G G hold the nail in position, with its head butting against the stop or back support C, and so that on working the hammer as if to drive a blow the nail, which projects beyond the face of the hammer-head, will be carried along with it and be entered or started in the work, which causes the hammer to release the jaws G G from the nail, that may then be driven home by striking it with the face end of the nose of the hammer in the usual manner. The jaws G G should be made just stiff enough to hold the nail until it is started in the wood, but not so stiff as to draw the nail out or even to pull it over when releasing their hold of it. They are made of considerable length, so that if the nail strikes a knot and glances they will yield and let the nail out and spring back to their place again. The clamp E with its attached jaws and tongue may be removed from the hammer and carried in the pocket of the operator when the nail-holding attachment is not required on the hammer.

The attachment will be found very useful to carpenters and others on high buildings, as the operator may hold himself securely with one hand, while doing the nailing with the other, thus avoiding the necessity of a scaffold or the splicing of a ladder for driving in a few nails, and under many other circumstances will it be found a very useful appendage, saving both time and labor and reducing the risk of accident or loss of life.

Instead of the attachment being made removable from the hammer, it may, if desired, be a permanent attachment thereto.

Having thus fully described my invention, I claim as new and desire to secure by Letters Patent—

1. The combination, with the spring-clamp E and spring-jaws G G, of the tongue F, attached to the spring-clamp, and constructed at

its rear end to enter the handle of the hammer for the purpose of anchoring the clamp on the head of the hammer, substantially as specified.

2. The combination, with the handle A and
5 hammer-head B, of the wedge or stop C in the outer end of the handle, the removable spring-clamp E, constructed to partly encircle and hug the nose of the hammer, the nail-holding spring-jaws G G, attached to the clamp, and the

tongue F, constructed to enter the outer end to of the handle and to anchor the clamp to its place, essentially as and for the purposes herein set forth.

GEO. F. BARBER.
